DESIGN FOR AN ELECTRIC SOLDERING DEVICE

Lembert H. Moulthrop, Bridgeport, Conn.

Application May 12, 1939, Serial No. 84,943

Term of patent 14 years

To all whom it may concern:

Be it known that I, Lembert H. Moulthrop, a citizen of the United States, residing at Bridgeport, in the county of Fairfield and State of Connecticut, have invented a new, original, and ornamental Design for an Electric Soldering Device, of which the following is a specification, reference being had to the accompanying drawing, forming a part thereof, in which

Figure 1 is a side elevational view of a solder-

ing device in an adjusted position showing my new design,

Figure 2 is a view looking at the top of Figure 1, and

Figure 3 is an elevational view looking from the right at Figure 1.

I claim:

The ornamental design for an electric soldering device, as shown.
